METHOD AND APPARATUS FOR FACILITATING THE PROCESSES OF PARTURITION

Ockert S. Heyns, Medical School, Hospital St., Johannesburg, Transvaal, Union of South Africa

Filed Jan. 9, 1957, Ser. No. 633,335

Claims priority, application Union of South Africa

2 Claims. (Cl. 128—361)

The process of parturition is naturally divided into three stages, in the first of which the cervical orifice of the uterus is caused to open preparatory to the expulsion of the foetus, while in the second stage the foetus and the uterus, opened during the first stage, are displaced towards the pelvic floor for the foetus to be expelled through the gap in the floor constituted by the vaginal canal. In the third stage the placenta is expelled. It is the second and third stages to which this invention refers.

The movements of all stages are produced by muscular contractions of the uterus induced automatically, and by movements of the abdominal diaphragm produced consciously.

The first and third stages and most of the second take place in the abdominal cavity, by which is meant the body cavity the walls of which are defined from above by the abdominal diaphragm, from below by the pelvic floor and at the sides by the abdominal walls. It has been ascertained that the pressure within the cavity is somewhat above atmospheric. The pressure is, of course, variable in that it is dependent upon the movements of the diaphragm, which, in the processes of parturition, is projected downwardly to promote or to induce the progress of the stages.

It has been established that the process of parturition is facilitated and quickened by setting up a pressure difference across a wall or walls of the cavity referred to above by reducing the pressure to the outside of at least part of the wall or walls.

The object of this invention is to provide apparatus suitable to apply this teaching to the second and third stages.

According to the invention, the apparatus consists in a bed having its head and foot zones hinged to its medial zone, means adjustably to raise the head zone to form a back rest, means to lower the foot end, a hole in the medial zone, a decompression chamber detachably secured to the bed and with a port registering with the hole, means to seal the chamber with the body of a patient on the bed around the pelvic outlet, a vacuum pump connected to the chamber through a valve, a window in the chamber, and a shutter to occlude the hole in the medial zone of the bed.

The development of this basic concept of the invention is dependent upon whether the parturition process is at the time in the first, the second or in the third stage.

An embodiment of the invention is shown in the accompanying drawings in which:

Figure 1 is a side view of a bed with the patient seated

2

on a decompression chamber during the second stage of labour, and

Figure 2 is a perspective view of part of the bed shown in Figure 1.

5 The apparatus illustrated in Figures 1 and 2 consists in a bed 25 the head end 26 of which is pivoted to be capable of being raised to form a back rest, as shown in Figure 1. The foot end 27 is inclined downwardly and can be raised to horizontality and clamped there by 10 a stay 28. Thus when the head end 26 is raised and the foot end 27 lowered the bed is transformed into a chair. The head end may be raised and lowered by a leadscrew and nut device 29. The medial portion 30 of the bed is fixed. It is formed with a hole 31. Underneath is 15 situated the upper end of a cylindrical decompression chamber 32, the top of which is gapped at 33 to form a port preferably of kidney shape with a soft rubber or rubber-like rim 34.

With the head end 26 of the bed raised, the patient 20 sits upon the decompression chamber, and the rim 34 of the port 33 causes the chamber to be sealed with her body around the pelvic outlet.

The decompression chamber 32 is connected by a pipe 36 to a vacuum pump 37.

25 Suction is applied to the pelvic outlet more or less in synchronism with the uterine spasms which accompany the second stage of labour; that is to say for periods of between 30 and 60 seconds, at intervals of say 60 seconds.

30 The pulsations of suction are continued until the delivery is imminent. To enable this point to be ascertained the chamber 32 is provided with a window 39, and an electric lamp 40 is mounted within the chamber.

The head end 26 of the bed is then lowered to bring 35 the patient to a recumbent position, a shutter 41 is slid into place over the hole 31 and delivery is effected.

Experience has shown that the results of the method of the invention during the second stage of labour are remarkable. The patient need not bear down, but the time taken for the foetus to move down the birth canal is materially reduced, if she does. Indications are that some births requiring instruments will proceed normally, and that some Caesarean operations will be rendered unnecessary.

40 45 The handling of the third stage of labour is akin to that of the second since again the method of the invention is to apply a differential pressure across the pelvic floor to assist in the extraction of the placenta. After delivery the shutter 41 is withdrawn, the head end 26 of the bed is raised and the foot end 27 lowered, to bring the patient into a sitting posture on the port 33, and suction is applied. It is found that by the method 50 of the invention the third stage of labour is in most cases reduced to a period of the order of one to three minutes, after the placenta has separated.

55 A highly important feature of the invention is that, after extraction of the placenta, the suction applied tends to cause strong contraction of the uterus and thus to avoid post-partum haemorrhage. Experience has shown that even where haemorrhage has occurred the effect of suction is to staunch the flow of blood and that it has not been necessary to administer oxytoxics.

60 It is scarcely necessary to say that in practice the chamber 32 is one of a set, to cater for women of different sizes. In the case of the chamber 32, the upper

part containing the rim 34 may be replaceable by any one of a set to vary the size of the rim.

Finally, it should be pointed out that the use of the apparatus very much increases the efficiency of the muscles of the uterus, and that there is no indication of ill effects to the mother or the child.

I claim:

1. Apparatus to facilitate and quicken the second and third stages of labour in childbirth, consisting in a bed having its head and foot zones hinged to its medial zone, means adjustably to raise the head zone to form a back rest, means to lower the foot end, a hole in the medial zone, a decompression chamber detachably secured to the bed and with a port registering with the hole, means to seal the chamber with the body of a patient on the bed around the pelvic outlet, a vacuum pump connected to the chamber through a valve, a window in the cham-

ber, and a shutter to occlude the hole in the medial zone of the bed.

2. The apparatus of claim 1 in which the port in the chamber that registers with the hole in the bed is defined by the sealing means.
